To all whom it may concern:

Be it known that I, Thomas Horan, a citizen of the United States of America and residing at New York, New York, have invented a new,
original, and ornamental Design for a Box Cover,
of which the following is a specification, reference being had to the accompanying drawing,
forming part thereof.

The figure is a perspective view of a box cover
showing my new design.

I claim:—

The ornamental design for a box cover as shown.

THOMAS HORAN.
